US00D967841S

(12) **United States Design Patent** (10) Patent No.: **US D967,841 S**
Walker et al. (45) Date of Patent: **** Oct. 25, 2022**

(54) **DISPLAY SCREEN WITH GRAPHICAL USER INTERFACE**

(71) Applicant: **Route App, Inc.**, Lehi, UT (US)

(72) Inventors: **Evan Walker**, Lehi, UT (US); **Mike Moreno**, Lehi, UT (US)

(73) Assignee: **Route App, Inc.**, Lehi, UT (US)

(**) Term: **15 Years**

(21) Appl. No.: **29/820,372**

(22) Filed: **Dec. 21, 2021**

CLAIM

The ornamental design for a display screen with graphical user interface, as shown and described.

DESCRIPTION

FIG. 1 is a front view of a first embodiment of a display screen with graphical user interface, showing our new design; and,

FIG. 2 is a front view of a second embodiment of a display screen with graphical user interface, showing our new design.

The broken lines showing a display screen and elements of the graphical user interface illustrate portions of the article, and form no part of the claimed design.

1 Claim, 2 Drawing Sheets
